UNITED STATES PATENT OFFICE.

ROBERT C. MENZIES, OF GLENS FALLS, NEW YORK.

STREET-CLEANER.

SPECIFICATION forming part of Letters Patent No. 664,878. dated January 1, 1901.

Application filed July 21, 1900. Serial No. 24,444. (No model.)

To all whom it may concern:

Be it known that I, ROBERT C. MENZIES, a citizen of the United States, residing at Glens Falls, in the county of Warren and State of New York, have invented a new and useful 5 Street-Cleaner, of which the following is a specification.

This invention relates to street-cleaners in general, and more particularly to that class 10 designed to be operated by hand, although it will be understood from the following description that the principles involved may be embodied in a cleaner drawn by horses or in any other manner.

15 The object of the invention is to provide a simple and efficient construction with which the dirt upon the street may be taken up and deposited in a receptacle, when latter may be removed when desired for dumping.

20 In the drawings forming a portion of this specification, and in which like numerals of reference indicate similar parts in the several views, Figure 1 is a plan view showing the complete implement. Fig. 2 is a side elevation showing the parts of the machine in position to receive the dirt in the pan, the positions of the parts when the dirt is discharged from the pan into the receptacle being shown 25 in dotted lines. Fig. 3 is a front elevation of the machine.

30 Referring now to the drawings, the machine comprises a frame including two U-shaped plates 5 and 6, of which the plate 5 lies in a vertical plane and the plate 6 lies in a horizontal plane, the ends of the sides of the plates being connected, as shown. At the 35 points of connection of the plates 5 and 6 are formed openings, through which are passed the ends of a bowed axle 7, which latter is 40 held rigidly to the sides of the plate 6 by clips 8 and to the web of the plate 6 by a clip 9.

The outwardly-directed ends of the axle 7, which lie in axial alinement, are provided with supporting-wheels 19, and in order that 45 the apparatus may be moved from place to place handles are provided. These handles (shown at 11) are formed by the sides of a U-shaped frame, the ends of which are secured under the clips 8 and which are further secured to the sides of the plate 6 by

additional clips 12. The web 13 of the U-shaped plate referred to connects the forward ends of the handle portions 11 and forms a handheld, which lies in advance of the mechanism of the machine.

55

The web of the plate 5 is adapted to receive and support a receptacle 14, which is shown as cylindrical, although it may be of other specific shape, and lies within the bow of the axle 7, the ends of the plate 6 being connected 60 by a chain 15, which passes around the rear side of the receptacle and holds it in its place upon the plate 5. As an additional support for the receptacle a plate 16 is secured to the web of plate 5 and is extended forwardly 65 therefrom to a point beneath the web or plate 6, where it is bent downwardly at right angles to form a foot 17 and is then bent upwardly to form a brace 18, and is attached at its upper end to the web 19 of plate 6. 70

Upon the sides of the plates 6, adjacent to the web thereof, are formed upwardly-directed lugs 20, which are perforated to receive interchangeably the pivot-pins 21, which are engaged also with the rear ends of the arms 75 22 of the pan 23. This pan 23 consists of a plate having its sides bent upwardly, as shown at 24, to form a scoop similar to an ordinary dust-pan, the sides being converged rearwardly and terminating at the rear edge 80 of the plate, where they are separated by an interspace 25, through which the contents of the pan may be discharged. The edge of the pan opposite to the discharge-opening is bent upwardly and is then bent forwardly 85 and downwardly to form an incline, which rests against the ground and over which the dirt may be brushed into the pan. When the pan has been filled, it is raised upon the pivots of the arms and its contents are discharged through the chute and into the receptacle. 90

To raise and lower the pan, the pan-arms 22 have extending plates 30, which lie above and at acute angles to the plates, and to their 95 outer ends are connected the ends of a bar 26, which forms a handle. Thus by manipulation of the handle the pan is raised and lowered. As above mentioned, the pivots of the arms 22 are movable, and thus the con- 100

nection of the arms may be adjusted to move the pan to the proper position under different conditions.

The operation of the machine is as follows:

- 5 The dirt in the street having been collected into piles, the machine is moved up to one of the piles and the pan is lowered into the position shown in Fig. 2 of the drawings. With an ordinary street-brush the dirt is then 10 brushed over the incline and into the pan, after which the handle of the pan is raised to bring the pan into the position shown in dotted lines in Fig. 2, when the dirt is discharged from the pan and into the receptacle, the discharge end of the pan lying then 15 above the mouth of the receptacle. After the dirt has been discharged the shovel may be returned to receive other dirt. When the receptacle has been filled, the chain may be 20 disengaged by removing the hook 29 at one end thereof from the perforation into which it is engaged, and the receptacle may be dumped or another may be substituted for it.

It will of course be understood that in practice various mechanical changes may be made 25 over the specific construction shown and that any suitable materials and proportions may be used for the various parts without departing from the spirit of the invention.

30 It is evident to those skilled in this art that the dirt may be brushed into the pan from the position in which it lies in the street instead of being first collected into piles; also, that the apparatus may be used in any other 35 manner to which it is adapted.

What is claimed is—

1. A street-cleaner comprising a supporting-frame having wheels and adapted to receive a dirt-receptacle, said frame extending 40 at one side of the axis of the wheels and provided with a supporting-foot adapted for movement into and out of contact with the ground as the frame is moved, and a pan pivotally connected with the extending portion 45 of the frame above the foot and adapted

for movement to discharge to the receptacle, whereby the weight of the pan and its contents will be borne by the foot.

2. A street-cleaner comprising a frame having supporting-wheels, said frame projecting 50 beyond the axis of the wheels, a supporting-foot carried by the frame beyond the vertical plane of the axis of the wheels, a handle connected with the frame for moving it to raise and lower the foot, arms pivoted upon 55 the frame above the foot, a pan carried by the arms and adapted to lie upon the street to receive dirt and to be raised to discharge to a receptacle upon the frame, and a handle for the pan.

3. A street-cleaner comprising a frame including two U-shaped plates disposed at right angles, a plate connecting the webs of the U-shaped plates and bent to form a supporting-foot, supporting-wheels connected with 65 the frame, and a pan pivoted to the frame and adapted for movement to alternately lie against the street and discharge to a receptacle upon the frame.

4. A street-cleaner comprising a wheel-supported frame including two U-shaped plates lying at right angles to each other, a plate connecting the webs of the U-shaped plates and bent to form a supporting-foot, a receptacle disposed upon the web of one of the 75 plates, a chain attached at its ends to the extremities of the U-shaped plates to hold the receptacle in position, a pan having arms pivoted to the frame, a handle for the frame and a handle connected with the pan to reverse it and cause it to discharge to the receptacle.

In testimony that I claim the foregoing as my own I have hereto affixed my signature in the presence of two witnesses.

ROBERT C. MENZIES.
